UNITED STATES PATENT OFFICE.

FREDERICK MANKEY, OF WILLIAMSPORT, PENNSYLVANIA.

DESIGN FOR A PANEL.

SPECIFICATION forming part of **Design No. 16,400**, dated **December 1, 1885**.

Application filed July 18, 1885. Serial No. 172,010. Term of patent 7 years.

To all whom it may concern:

Be it known that I, FREDERICK MANKEY, of Williamsport, Lycoming county, Pennsylvania, have invented and produced a new and original Design for Open-Work Panels, of which the following is a specification, reference being had to the accompanying photograph, forming part hereof.

My design consists of a panel in the form of a grating having longitudinal bars A and transverse bars B, with intermediate rectangular openings, C. The edges of said openings are beveled or rounded. Longitudinally across the panel and intermediately between the bars A are formed channels or grooves F. Trans-

versely across the panel and intermediately

between bars B are formed channels or grooves G. At the centers of the intersections of the bars A and B, I may form circular indentations E. The resulting design has the appearance of an assemblage of Greek crosses placed in contact, as shown.

I claim—

The design for an open-work panel, substantially as herein shown and described, consisting of the longitudinal bars A, transverse bars B, rectangular openings C, with beveled edges, and grooves F and G.

FREDERICK MANKEY.
